UNITED STATES PATENT OFFICE.

EDWIN T. MARSH, OF ROCHESTER, NEW YORK.

BALING-PRESS.

1,296,830.

Specification of Letters Patent. Patented Mar. 11, 1919.

Application filed February 27, 1918. Serial No. 219,489.

To all whom it may concern:

Be it known that I, EDWIN T. MARSH, a citizen of the United States, residing at Rochester, in the county of Monroe and State 5 of New York, have invented certain new and useful Improvements in Baling-Presses; and I do declare the following to be a full, clear, and exact description of the invention, such as will enable others skilled in the art 10 to which it appertains to make and use the same.

My invention relates to improvements in baling presses and more particularly to those of the type commonly employed for baling 15 waste paper and the like.

One object of the invention is to provide a baling press of the character set forth which may be easily knocked down and crated for shipment and then assembled easily for use. 20 A further object is to provide a screw for initially depressing the follower after filling of the baling box or chamber, to provide a hand lever for again depressing the follower after insertion of more material, and to provide a novel device for holding the follower in its completely depressed position while 25 the bale is being tied.

With the foregoing general objects in view, the invention resides in the novel features of construction and unique combinations of parts to be hereinafter fully described and claimed, the descriptive matter being supplemented by the accompanying drawings which form a part of this specification 30 and in which:

Figure 1 is a perspective view with part of the front side of the baling box broken away and in section showing the use of the screw for initially depressing the follower;

Fig. 2 is a vertical section of the device 40 when the screw is being employed;

Fig. 3 is a perspective view showing the manner in which the follower is depressed by the hand lever, and secured in depressed position by the vertically swinging arm, this view also disclosing the manner in which the front side of the baling box is swung outwardly for tying the bale;

Fig. 4 is a detail perspective view of the upper end of the baling box, showing more particularly the manner in which the link forming the fulcrum of the hand lever is mounted;

Fig. 5 is a horizontal section showing 50 principally the manner of hingedly and de-

tachably connecting the sides and ends of the baling box;

Fig. 6 is a perspective view showing more particularly the form of connection between the box bottom and the rear side of the 60 box; and

Fig. 7 is a detail section of the upper end of the jack.

In the drawings above briefly described, the numeral 1 designates a vertically disposed rectangular baling box whose front and rear sides S and S' respectively, and its ends E and E', are provided with transverse reinforcing cleats 2. By hinges 3, the cleats of the end E are connected to the cleats of the rear side S', and by hinges 3', the other end E' is hinged to the front side S. Hinged hasps 4 detachably connect the cleats of the end E with the front side S and similar hasps 4' connect the cleats of the end E with the rear side S'. The bottom B of the box is detachably connected to the ends E and E' by hinged hasps 5 and by means of hinges 6, the rear edge of said bottom is attached to the rear side S' of the 80 box.

The arrangement of parts just described for connecting the several portions of the box 1, permits the box to be quickly and easily knocked down for crating and shipment, yet permits the device to be easily set up for use when received. The hinges 3' and hasps 4 also permit the front side S to be swung outwardly as shown in Fig. 3 for 85 tying of the bale.

The upper edge of the rear wall S' is formed with a pair of notches 7 to receive one end of the tying cords 8, said cords depending from said notches on the interior of the box and then extending forwardly 90 across the bottom B through other notches 9 in the lower edge of the front S. The cords then rise on the exterior of the box and have their inner ends passed into notches 10 formed in the upper edge of the 100 front S. With the cords in this position, a layer of card board or other suitable material 11 is placed upon the bottom of the box and the waste paper or other material to be baled is then packed into said box. 105 This having been done, a follower 12 is placed upon the material which has previously been packed as much as possible. A follower depressing screw 13 is then interposed between the follower and a pivoted 110

bail 14 which extends across the open top of the box, said screw being operated by a hand lever or the like 15 to depress the follower 12 so that the material in the box is 5 suitably compressed. After this has been done, the screw 13 and the follower 12 are removed, and more material is placed in the upper end of the box. The follower is then inverted and again placed in position.

10 A hand lever 16 is now employed for depressing the follower, one end of this lever being passed through an open link 17 while a suitable block 18 is interposed between the follower and the lever (see Fig. 3). When 15 the follower has been sufficiently depressed in this manner, an arm 19 which is pivoted thereto at 20 is swung upwardly beneath the bail 14 as shown in Fig. 3 and is held in upright position by a hook or the like 21.

20 The hand lever 16 and block 18 are now removed and the front S of the box 1 is swung outwardly, thus permitting tying of the cords 8. It may here be explained however that before the follower 12 is inserted for 25 the second time, the rear ends of these cords are brought forwardly across the upper end of the bale.

To pivot the bail 14 to the box, its ends are bent outwardly at 22 through the box ends 30 E and E' and their cleats 2, and the cleat of the end E' is formed of a notch 23 across which one of the ends 22 extends. The lower end of link 17 is received in the notch 23 and said end 22 passes through said link to anchor the latter. This detail is a rather 35 important feature in a knock down baling press of the character described, since it simplifies the construction and eliminates the necessity of other attaching means for the 40 link.

The jack screw 13 is threaded in a base 13^a and the upper end of said screw is provided with a squared extension 13^b upon which is fitted a collar 15^a to which the lever 15 is 45 pivoted at 15^b. A stud 13^c rises from the extension 13^b and is rotatably received in an opening in the bottom of a channel shaped head 14^a which receives the bail 14 when the jack is in use, the upper end of the stud

being upset or riveted to permanently attach the head and collar. 50

From the foregoing, taken in connection with the accompanying drawings, it will be obvious that although my invention is of extremely simple and inexpensive nature, it 55 will be highly efficient and durable, particular emphasis being laid upon the knock down characteristics, upon the provision of the arm 19, and upon the novel attaching means of the link 17. Since probably the 60 best results are obtained from the details shown and described, such details are by preference employed, but within the scope 65 of the invention as claimed, numerous minor changes may well be made.

I claim:

1. A baling press comprising an upright box open at its top, a pivoted bail extending across said open top, a follower for reception in said box, a hand lever for depressing said follower, and an arm pivoted to the upper side of said follower and adapted to be swung upwardly to a vertical position with its upper end abutting said bail, whereby to hold said follower in lowered position while 75 tying the bale.

2. A baling press comprising an upright box open at its top and having transverse cleats secured on the outer side of its wall, one of said cleats having a notch in its inner side, a follower, a bail extending across the open top of said box and having its end bent laterally through the sides thereof, a link having its lower end positioned in said 80 notch, one end of said bail extending across said notch and through said link, a hand lever receivable at one end in said link for depressing said follower, and follower holding means coöperable with said bail and 85 said follower.

In testimony whereof I have hereunto set my hand in the presence of two subscribing witnesses.

EDWIN T. MARSH.
